UNITED STATES PATENT OFFICE.

MAUDE M. DORAN, OF SPOKANE, WASHINGTON.

COUNTER AND HEEL GUARD.

Application filed October 27, 1926. Serial No. 144,566.

The object of this invention is to provide a novel form of protecting device for guarding rear portions of the heel and counter of the shoe from being scuffed and defaced as a result of manipulating the treadles of an automobile.

It is well known that rear portions of the shoes of drivers soon become worn and defaced by frequent rubbing contact with the floor mats of automobiles by reason of the tilted position which the foot occupies in operating the gas, brake and other treadle devices. This is especially true with ladies' shoes by reason of the fact that the high heels recede from the counter thereby exposing the latter to extreme localized wear on the rear portions thereof.

It is an object of my invention to provide a protecting device in the form of a guard made up of one integral piece of material that is provided with means whereby the guard may be readily attached to and detached from the heel of the shoe.

It is a further feature of my invention to make the guard of resilient or elastic material such as rubber, and to provide the guard with attaching means that must be distended when attached to the heel, the guard being acted upon by such distension in such a manner that the guard will be held in protecting relation to the counter and heel.

My invention has many other features and objects which will be more fully described in connection with the accompanying drawing and which will be more particularly pointed out in and by the appended claims.

In the drawing:

Fig. 1, is a view in side elevation generally illustrating the position of the foot in connection with the gas treadle of an automobile, the guard of my invention being shown applied to a ladies shoe.

Fig. 2, is an enlarged view in side elevation showing the guard more clearly and illustrating how it can be worn without impeding the user in walking.

Fig. 3, is a view looking from the left of Fig. 2.

Fig. 4, is a sectional view on line 4-4 of Fig. 2.

Fig. 5, is a plan view of the guard showing the same before it is applied to a shoe and in its normal condition.

Fig. 6, is an edge view thereof.

Like characters of reference designate similar parts throughout the different figures of the drawing.

I have shown the device of my invention applied to a low shoe 1, although by reason of the novel attaching means with which my guard is provided, it is equally adapted to any type of shoe.

In the preferred form, the guard 2 is formed from a sheet or strip of material such as rubber, having the essential requirements of pliability and extensibility and elasticity that will permit of the guard adapting itself to shoes of various sizes and shapes and performing its function on each, with equal facility, thereby avoiding the necessity of making a number of sizes of the guard.

The guard, as shown, is a vertically elongated shaped device, the upper portion 3 being of slightly greater width than the lower portion 4. In practice, I prefer to make the guard of a single piece of relatively thin rubber which, in its normal condition and in the absence of stress, will lie in a single plane, the size shown being full size. The guard is proportioned to be horizontally arched about the rear of the counter and heel of the shoe, the guard extending laterally a sufficient distance to protect the shoe from any wear and defacement that it could possibly suffer, in the performance of the function shown in Fig. 1.

I will next describe a means with which the guard is equipped for the purpose of permitting the guard to be readily attached to or detached from a shoe.

As shown, I provide the guard with a slit 5 which is near enough to the lower edge 6 to afford stock for a heel engaging strap or band 7. It will be noted that this slit or slot 5, is substantially horizontally disposed, with reference to the position of the guard shown in Fig. 5, and that it extends across the reduced lower portion of the guard and toward but not to the side edges 8 thereof. Thus, there is ample stock 9, between the terminal ends of the slit 5, and the edges 8, for the durable performance of a function which I will later describe.

In applying the guard to a shoe, the slitted portion is distended with the main body of the guard abreast of the counter 10, of the shoe. The strap or band 7, is disposed

abreast of the front face 11, of the heel 12, and then the upper end 3, is pulled upwardly to dispose the guard at the desired height, as clearly shown in Fig. 2. It makes a neater 5 appearance when applying the guard, to turn the band 7 so that the reverse side 13, of the band 7, is disposed outermost while the face 14 thereof is against the front of the heel, as shown. However, this is not an 10 essential feature as the guard will be firmly held in place irrespective of the disposition of the band 7. However, a very valuable 15 feature consists in reducing the total length of the slit 5, with respect to the circumference of the heel 12, so that when the latter is encircled with the slotted portion of the guard, the material of which the latter is composed will be placed under tension. By 20 so tensioning the guard, the main body is drawn against the counter of the shoe and is horizontally arched about the latter, as a 25 form, thereby neatly fitting the shoe.

It will now be clear why I feature the idea 25 of leaving a sufficient amount of stock at 9, between the ends of slit 5 and the edges 8, the purpose being not only to preserve the 30 length of the slit 5, but also to provide stock for transmitting the stress resulting from tensioning the slit, to upper portions of the 35 guard to thereby hold the latter in place.

When the guard is applied, the upper bight 15, of the slit 5, is extended about the 40 rear and side portions of the heel 12, whereas, the lower portion or bight 16, of the slit 45 is extended about the front and side portions of the heel. Now when the band 7, is reversed, as shown, there is imparted to the 50 body of the guard a very pronounced stress tending to hold the guard in the position 55 shown in Fig. 2.

It will be noted that the heel, below the 60 guard, is free and uncovered and likewise 65 unobstructed, and that the guard does not extend to the bottom of the heel. Hence, if 70 the wearer wishes to alight from the automobile to enter a store, or for any purpose, the 75 guard need not be detached since its presence

does not in any way impede walking while the guards are attached.

It is believed that the device of my invention will be fully understood from the foregoing description and while I have herein shown one specific form of my invention, I do not wish to be limited thereto except for such limitations as the claims may import. 55

I claim:

1. In a shoe counter and heel protecting device, a normally flat sheet rubber guard proportioned to encase the rear portions of the heel and counter, and said guard having a heel receiving slit therethrough sufficiently close to the lower edge of said guard to form a relatively narrow heel engaging band adapted to extend around the front portion of the heel, the length of said slit being sufficiently reduced with respect to the circumference of the heel to tension and arch the guard about the heel and counter when the slotted portion is stretched about the heel, thereby holding the remainder of the guard in protecting relation about the heel and counter. 65

2. In a shoe counter and heel protecting device, a sheet rubber guard having a slit therethrough adjacent one edge and terminating between the side edges of and providing the guard with a heel engaging band, the upper bight of said slit being adapted to encircle rear portions of the heel and the lower bight of said slit encircling front portions of the heel under sufficient tension to horizontally arch the guard in protecting relation about the heel and counter. 75

3. In a shoe counter and heel protecting device, a rubber sheet guard proportioned to extend vertically along the rear of the heel and counter of a shoe, said guard having means adapted to engage the heel for holding said guard in position and arching said guard about the heel and counter. 85

In witness that I claim the foregoing as my own, I hereby affix my signature. 90

MAUDE M. DORAN.
